Inventor,
Dalton K. Wilson, by
G. O. Kennedy,
Attorney.

UNITED STATES PATENT OFFICE.

DALTON K. WILSON, OF WATERLOO, IOWA.

COMBINATION TABLE.

Application filed December 11, 1924. Serial No. 755,303.

To all whom it may concern:

Be it known that I, DALTON K. WILSON, a citizen of the United States, residing at Waterloo, in the county of Black Hawk and State of Iowa, have invented certain new and useful Improvements in Combination Tables, of which the following is a specification.

My invention relates to improvements in combination tables, and the objects of my improvements are these, first, to provide for kitchen or other use a table having collapsible and sliding parts for employment as auxiliary supporting means and attachments, and second, to supply in combination with the table an ironing board attachment constructed for adjustable attachment thereto.

These objects I have accomplished by the means which are hereinafter described and claimed, and which are illustrated in the accompanying drawings, in which, Fig. 1 is a perspective view of my improved combination table with parts extended, ready for use. Fig. 2 is a top plan of the devices as shown in said Fig. 1, with parts broken away, and having the said ironing board mounted adjustably and detachably thereon. Fig. 3 is an end elevation, showing said ironing board, but showing parts collapsed or closed upon the table.

Minor changes or variations of construction of said invention are nevertheless covered by the principle of the same.

The table has a solid top 3 supported on legs 1, with said top projecting beyond the legs on every side, but projecting farther at the sides than at the ends to supply knee room.

The front of the table is shown in said Fig. 1, having a top molding or panel 2 containing an opening for a sliding drawer 4 at the right. Near the lower ends of the legs 1 in front another panel or crosspart is open to seat another sliding drawer, below a compartment having a pair of doors 5 swinging on hinges 6. The rear and the ends of the table between said legs have closure walls as at 8, but the left-hand wall 8 is spaced at its top from the table top 3 to provide an opening 9.

An auxiliary table leaf 10 is hinged at 11 to the top 3 to swing downwardly. A pair of fixed lugs 13 are mounted to depend

from the middle of the under side of the leaf 10. The numeral 16 denotes a swinging prop whose lower end may contact with a block 12 on the adjacent wall 8. This prop has a pair of upright parts 15 which are pivoted between the lugs 13 on pintles 14, so that when the prop 16 is swung rearwardly, and against the under face of the leaf 10, the latter may be swung downwardly to hang adjacent to the end of the table.

As shown in Fig. 2, slideways 21 are fixed oppositely within the table horizontally and attached to the front and rear walls thereof to terminate at the left at the lower part of said opening 9. Stop-bars 22 are fixed thereabove in spaced relation.

The numeral 24 denotes a removable tray or sliding shelf with raised rim which slides in the interspaces of the fixed bars 21 and 22 in and out of the opening 9, but in practice not entirely withdrawn from said slideways. Upon this sliding shelf 24 may be removably mounted any kind of object, such as a small gas or electric heater 25, to slide together with the shelf into the interior of the table through the opening 9. A cross-bar 23 may be fixed across the two bars 21 as a support and a stop.

The numeral 19 denotes an auxiliary leaf having a pair of spaced projections 20 whose terminations are pivoted on pintles 18 to the lower ends of fixed hangers 17 to swing downwardly. The interspace of the projections 20 is large enough to clear and surround the projected part of the sliding shelf 24 when the leaf is horizontal, and a pivoted button 36 on the leaf 19 may be turned over the adjacent rim of the shelf 24 to support the leaf in its raised position. Another auxiliary leaf 27 has end projections 28 also pivoted on said pintles 18, the leaf being of a length to fit within the interspace of the projections 20 to swing downwardly. After the shelf 24 has been pushed entirely into the slideways 21-22 within the interior of the table, and the released leaf 19 swung downwardly as in Fig. 3, the leaf 27 may be swung upwardly to close the said opening 9. The leaf 19 is suitable for the support of utensils used in cooking.

In Figs. 2 and 3 I have shown an ironing board 29 supported across the table top 3 to have its diminished part projecting for

wardly therefrom horizontally. While the top 3 is square, it may be otherwise shaped, for the board 29 is supplied with clamping members arranged for adjustably attaching it to the table detachably. On the rear end of said board 29 is fixed a hooked clamping member 30 to clasp the rear edge of the table top 3. A plate 32 is positioned against the middle of the under surface of the board 29 and has a longitudinal slot 35 with any part of which a bolt hole in said board may register, a bolt 34 being passed through both and releasably secured by a wing-nut 33. The plate has its left-hand part offset downwardly to provide a clamping member 31 to coact with the member 30 in clamping the table top adjustably between them to thus secure the board 29 from accidental displacements. The board 29 may be removed when not in use.

This combination table is contrived for use in small kitchens or apartments where compactness is desired, and convenience for employment in different ways as possible by the said means provided.

Having described my invention, what I claim as new, and desire to secure by Letters Patent, is:

1. In a device of the character described, a table containing an open end slideway, a slide slidably mounted in said slideway to be shifted in or out of said open end, a U-shaped leaf having its members hinged to said table to inclose the projection of said slide when lifted, and releasable means for supporting said leaf upon said slide when both are extended.

2. In a device of the character described, a table containing an open end slideway, a slide slidably mounted in said slideway, a leaf hinged to said table and having an opening to receive said slide when both are positioned in extension from the table, and a closure hinged to said table to swing through the opening of said leaf when retracted and when the slide is shifted to clear the opening, said closure being then adapted to close the open end of the slideway.

In testimony whereof I affix my signature.
DALTON K. WILSON.
